UNITED STATES PATENT OFFICE

JACOB J. KAGAN, OF LOS ANGELES, CALIFORNIA

DESIGN FOR A RING

Application filed November 15, 1930. Serial No. 37,673. Term of patent 14 years.

To all whom it may concern:

Be it known that I, JACOB J. KAGAN, a citizen of the United States, residing at Los Angeles, in the county of Los Angeles and State of California, have invented a new, original, and ornamental Design for a Ring, of which the following is a specification, reference being had to the accompanying drawing, forming part thereof.

The figure shows a perspective view of my finger ring design. The love birds are the same on both sides of the ring, as well as the other parts.

I claim:

The ornamental design for a ring, as shown and described.

In testimony whereof, I hereunto set my hand.

JACOB J. KAGAN.
